US0D1106467S

(12) **United States Design Patent** (10) **Patent No.:** **US D1,106,467 S**
(45) **Date of Patent:** **** Dec. 16, 2025**

(54) **WOUND DRESSING**

(71) Applicants: **Winner Medical Co., Ltd**, Shenzhen (CN); **Winner Medical (Huanggang) Co., Ltd**, Huanggang (CN)

(72) Inventors: **Jianquan Li**, Shenzhen (CN); **Zhilun Zhou**, Shenzhen (CN); **Yujia Wang**, Shenzhen (CN); **Ruizhen Zhang**, Shenzhen (CN)

(73) Assignees: **Winner Medical Co., Ltd**, Shenzhen (CN); **Winner Medical (Huanggang) Co., Ltd**, Huanggang (CN)

(**) Term: **15 Years**

(21) Appl. No.: **29/960,923**

(22) Filed: **Sep. 3, 2024**

(30) **Foreign Application Priority Data**

Aug. 5, 2024 (CN) 202430491605.X

(57) **CLAIM**

The ornamental design for a wound dressing, as shown and described.

DESCRIPTION

FIG. 1 is a perspective view of a wound dressing, showing our design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

(Continued)

FIG. 9 is an exploded view thereof.

1 Claim, 9 Drawing Sheets
